UNITED STATES PATENT OFFICE.

SAMUEL M. SCHWAB, JR., OF NEW YORK, N. Y.

DESIGN FOR A PATTERN FOR PRINTED FABRIC.

SPECIFICATION forming part of Design No. 21,858, dated September 13, 1892.

Application filed June 27, 1892. Serial No. 438,217. Term of patent 7 years.

To all whom it may concern:

Be it known that I, SAMUEL M. SCHWAB, Jr., a citizen of the United States, residing at New York, in the county and State of New York, have invented and produced a new and original Design for Fabric, of which the following is a specification, reference being had to the accompanying drawing, forming a part of this specification, which represents a plan view of a piece of fabric embodying the features of the design.

The design consists of figures simulating dogs arranged in pairs, each figure surrounded by a somewhat shadowy line, and adjacent to

the two dog-like figures two other figures are arranged, and each of these two figures simulate the lower body and leg portions of the animals represented upon the fabric. The figures simulating the lower body and leg portions of the animals also appear as surrounded by spaced or shadow-like lines.

I claim—

The design for a pattern for printed fabric, substantially as herein shown and described.

SAMUEL M. SCHWAB, JR.
